UNITED STATES PATENT OFFICE.

LYMAN G. KEYES, OF NATIONAL MILITARY HOME, KANSAS.

DOUBLE-DOOR BOLT.

1,241,991.

Specification of Letters Patent.

Patented Oct. 2, 1917.

Application filed May 15, 1917. Serial No. 168,626.

To all whom it may concern:

Be it known that I, LYMAN G. KEYES, a citizen of the United States, and a resident of National Military Home, in the county 5 of Leavenworth and State of Kansas, have invented a new and Improved Double-Door Bolt, of which the following is a full, clear, and exact description.

This invention relates to locking devices 10 for double doors, double hinge window sashes and the like, employed in homes, public buildings, schools, garages, barns, etc., where one section of the door or window is used for ordinary ingress and egress, but 15 where both doors or sashes may be instantly opened when desired.

The invention has for its general objects 20 to provide an improved operating means for the head and foot bolts of the locking device, so as to be reliable and efficient in use, comparatively inexpensive to construct, of durable and substantial design, and capable of being readily adjusted to place the operating handle or lever in the best position.

25 A more specific object of the invention is the provision of bolt-operating means which is so designed as to insure positive, easy and smooth movement of the bolts, and including means whereby the operating handle can be adjustably connected to the bolts in a simple, secure and efficient manner.

With such objects in view, and others which will appear as the description proceeds, the invention comprises various novel 35 features of construction and arrangement of parts which will be set forth with particularity in the following description and claims appended hereto.

In the accompanying drawing, which 40 illustrates one embodiment of the invention and wherein similar characters of reference indicate corresponding parts in all the views,

Figure 1 is a view of the inside of a double 45 door with the locking means applied thereto;

Fig. 2 is an enlarged view of the bolt-operating means;

Fig. 3 is a vertical section on the line 3—3, Fig. 2;

50 Fig. 4 is a vertical section on the line 4—4, Fig. 2;

Fig. 5 is a horizontal section on the line 5—5, Fig. 2;

55 Fig. 6 is a detail sectional view on the line 6—6, Fig. 2;

Fig. 7 is a front view of the base plate; and

Fig. 8 is a front view of the connecting disk between the operating handle and the bolts.

Referring to the drawings, 1 and 2 designate separate doors which swing on hinges 3 and one being held in closed position by head and foot bolts 4 and 5 which engage respectively in sockets 6 and 7.

The bolts are adapted to be moved to and from locking position by an operating device A which comprises a handle or lever 8 which is adjustably connected with a disk 9 which, together with the handle, is fastened by a pivot bolt 10 which screws into the base plate 11 fastened to the door 2, and on the disk 9 are pins 12 disposed at diametrically opposite points by which the bolts 4 and 5 are pivotally connected with the disk. The pivoted ends of the bolts lie under the disk or between the same and the base plate, which latter has a central boss 13 to form a spacer between the base plate and the disk to accommodate the bolts. The base plate has arcuate recesses 14 concentric with the central pivot 10, and the pins 12 have a sliding engagement in the recesses to limit the movement of the bolts in the operation of the locking device. The disk 9 is fastened to the handle 8 by a screw 15, the head of which is countersunk in the disk, as clearly shown in Fig. 6, said disk being provided with a plurality of apertures 16, whereby the screw can be placed in any aperture to adjustably connect the handle with the disk. To insure positive action between the handle and disk the latter on its front face has a plurality of spaced projections 17 any one of which is engageable in a depression 18 in the under side of the handle 8, as clearly shown in Fig. 6. By this means the handle can be adjusted to the disk and thereby adjustably related to the bolts so as to place the handle in any desired position.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire

to have it understood that the device shown is merely illustrative and that such changes may be made when desired as fall within the scope of the appended claims.

5 Having thus described my invention, I claim as new and desire to secure by Letters Patent:

1. A bolt operating device comprising a base plate having a raised portion and arcuate slots, a stud projecting from the raised portion, a disk on the stud and extending outwardly beyond the raised portion, whereby a recess is provided between the disk and plate, bolts extending into the recess and located at opposite sides of the raised portion, means forming pivots between the disk and bolts and also forming members engaged in the slots of the base plate to limit the turning movement of the disk, and 20 means connected with the disk for turning the same.

2. The combination of a plurality of bolts, with operating means therefor comprising a base plate, a central pivot stud thereon,

said base plate having arcuate slots concentric with the stud, a disk on the stud, pins on the disk and to which the bolts are pivotally connected, said pins extending into the arcuate slots, a handle on the stud, and means for adjustably fastening the handle to the disk.

3. The combination of a plurality of bolts, with operating means therefor comprising a base plate, a central pivot stud thereon, said base plate having arcuate slots concentric with the stud, a disk on the stud, pins on the disk and to which the bolts are pivotally connected, said pins extending into the arcuate slots, a handle on the stud, means for adjustably fastening the handle to the disk, interengaging means between the handle and disk, whereby the handle can be adjusted to different angular positions, and fastening means securing the disk and handle together and holding the same interlocked.

LYMAN G. KEYES.
